UNITED STATES PATENT OFFICE.

JOHN CHESNEY, OF PAULSBORO, NEW JERSEY, ASSIGNOR TO THE E. I. DU PONT DE NEMOURS POWDER COMPANY, OF WILMINGTON, DELAWARE, A CORPORATION OF NEW JERSEY.

MACHINE FOR MAKING PAPER SHELLS.

No. 892,362.

Specification of Letters Patent.

Patented June 30, 1908.

Original application filed December 11, 1906, Serial No. 347,380. Divided and this application filed October 25, 1907.
Serial No. 399,107.

To all whom it may concern:

Be it known that I, JOHN CHESNEY, a citizen of the United States, residing at Paulsboro, county of Gloucester, and State of New Jersey, have invented a new and useful Improvement in Machines for Making Paper Shells, of which the following is a full, clear, and exact description, reference being had to the accompanying drawings, which form a part of this specification.

The invention relates to that class of machines for making paper shells for holding explosives in which the paper sheets are fed to a rotating mandrel and wrapped thereon to form a tube, the end of which is folded and closed and which is then slipped off the mandrel.

The object of the invention is to provide means, coöperating with the means for conveying the sheets to the mandrel, for printing each sheet of paper before it is fed to the mandrel.

This application is a division of an application filed by me December 11th, 1906, Serial No. 347,380, in which the construction and operation of the whole machine are set forth. In the present application, only the parts of the machine embodying my invention and the parts immediately coöperating therewith are illustrated and described.

In the drawings: Figure 1 is a plan view of the machine. Fig. 2 is a side elevation of a part of the machine embodying my invention. Fig. 3 is a front elevation with certain parts omitted to more clearly show the remaining parts. Fig. 4 is an enlarged detail sectional view of the pneumatic picker. Fig. 5 is an enlarged detail sectional view of the stamp. Figs. 6 and 7 are detail sectional views of the pressure and exhaust valves respectively.

9 is the top plate of the machine frame, 10 is the vertically movable table holding the sheets of paper *a*. The stationary side-plate 100 of the table 10 is bolted to the angle-bar 101, which is bolted to the top plate 9 of the frame.

20 is the mandrel to which the sheets of paper are successively fed and about which the paper is wound to form the paper tubes.

10 is a pneumatic picker and feeder for

picking up the paper sheets and feeding them to the mandrel. The picker and feeder 40, shown in detail in Fig. 4, comprises the hollow head 41, connected to and supported by the exhaust pipe 50, the hollow shank 42 depending from the head 41, and the mouthpiece 43 surrounding and sliding on the shank 42. The exhaust pipe 50 extends through and is supported by an arm 45 on the slide 46, and communicates with the exhaust chamber 13. The slide 46 is movable back and forth on side-plate 100 as a guide.

Secured to the slide 46 is a bar 47 whose rear end is attached to a lever 48 pivoted on a bracket 38 on the top plate 9. A spring 51, secured to the bracket 38 and bearing against the lever 48, normally holds the slide 46 in its backward position against a stop 52 secured to the side-plate 100. A cam 49, on the main driving-shaft 11, moves the lever 48 forward against the tension of the spring 51 and moves the slide 46 toward the mandrel.

110 is the driving pulley for the main shaft.

Interposed in the pipe 50 is a valve 54, (see Fig. 7) normally held, by the spring 55, against its seat to close communication between the exhaust chamber 13 and the picker and feeder 40; but the stem 56 of the valve is operated at the proper time by a cam 59 on the main driving shaft 11. When the valve 54 is thus operated, the air is sucked inwardly through the shank 42, the mouth piece 43 sliding upwardly on the shank and lifting the top sheet above the pile below it. The suction being maintained, the picker and feeder is moved forwardly toward the mandrel by the described action of cam 49. This brings the front edge of the sheet over and against the upper face of the rotating mandrel 20. The cam 59 then passes beyond the valve-stem 56, and the valve closes, shutting off communication between the exhaust cylinder 13 and the picker and feeder 40, and releasing the sheet fed to the mandrel. The cam 49 subsequently passes beyond the lever 48, which is moved backwardly by means of the spring 51, returning the picker and feeder 40 to its original position.

A holder 47', consisting of a plate secured

to the mouth-piece 43, and extending forwardly on a level with the lower edge of the mouth-piece, continues to engage the forward end of the pile when the picker and feeder is moved to its furthest position back, and prevents the mouth-piece of the picker and feeder from catching in the top sheet or sheets of the paper as it moves forwardly.

10 The mandrel is detachably secured to a hollow shaft 21 turning in bearings in standards 22. After the sheet is carried forward to the mandrel and released from the picker as before described, means are provided to 15 hold the sheet against the mandrel, to rotate the mandrel-shaft, to fold in and head the end of the tube thus formed and to eject the finished tube; but this mechanism is not herein shown or described, as it forms no part of 20 the invention herein claimed.

The table 10 is supported on the top of an upright screw-shaft 15, whose flanged upper end fits rotatably within a cap 102 on the under side of the table. Means, not herein 25 shown or described, are provided to cause the feed shaft to be turned and moved a very slight distance upwardly after the recession of the picker and feeder 40, the extent of upward movement of the screw-shaft just 30 equaling the thickness of a piece of paper, whereby the top of the pile is maintained on a constant level.

To print each sheet of paper before it is fed to the mandrel, the following device, 35 (shown in detail in Fig. 5) is provided. 17 is a stamp-block on a plunger-rod 170 extending within a cylinder 171. 172 is the plunger head fitting within the cylinder. 173 is a spring tending to hold the plunger and stamp-block raised. The cylinder 171 is secured to and communicates with a pipe 174 connected with the pressure cylinder 12. The pipe 174 extends through a bracket 175, which is secured to the side-plate 100 by means of a set 40 screw extending through one of the several orifices 105 in the side-plate. Passage of pressure fluid through the pipe 174 is controlled by a valve 860 (similar to valve 54) whose stem 88 is operated, against the pressure 45 of spring 87, by a cam 179 on the main shaft. When air is admitted through the pipe 174 to the cylinder 171, it forces the face of the stamp-block 17 against the surface of the top sheet and prints thereon. To ink the 50 printing face of the stamp block, I provide a roller-pad 18 journaled in the lower ends of levers 180 pivoted on an arm 181 on the cylinder 171. Springs 182, connecting the cylinder and the levers, tend to hold the roller 55 under the stamp-block, but when the plunger-rod 170 is depressed, the roller 18, being held from downward movement, swings outwardly, and clears the stamp-block. When

the plunger is retracted, the springs 182 return the roller to its normal position. Projecting from the cylinder 171 are arms 176 65 carrying guides 177 through which extend rods 178 secured to the stamp-block 17.

To prevent the paper on the table from creeping forwardly, there is provided the 70 holding-plate 191 secured to the top-plate 9, which extends up to a point that enables the top sheet to be fed over it to the mandrel.

192 is a stop secured to the table and extending in back of the pile and preventing 75 the paper from slipping backwardly.

193 is a holder at the side of the paper, the same consisting of an angle plate secured to the table and extending up along side, and also overhanging the pile. 80

Having now fully described my invention, what I claim and desire to protect by Letters Patent is:—

1. In a machine for making paper shells, the combination with the table for holding 85 the pile of paper, and means to convey sheets of paper from the table, of a stamping block over the pile, a plunger secured to the stamping block, a cylinder into which said plunger extends, a pressure cylinder, a pipe connecting the pressure cylinder and plunger, the driving shaft, means actuated by the driving shaft to operate said conveying means, a valve in said pipe, and means actuated by the driving shaft to actuate said valve and 95 force said block against the pile while the conveying means is inoperative.

2. In a machine for making paper shells, the combination with the table for holding 100 the pile of paper, of means to convey sheets of paper from the table, a stamping block above the table, a plunger secured to the stamping block, a cylinder into which said plunger extends, a pressure cylinder, a pipe 105 connecting the pressure cylinder and plunger, the driving shaft, a valve in said pipe, and means actuated by the driving shaft to actuate said valve while the paper-conveying means are inoperative, an inking roller beneath the stamping block, and means pivotally supporting the inking roller from said cylinder and permitting the inking roller to move laterally when the plunger is depressed.

3. In a machine for making paper shells, 115 the combination with the table for holding the pile of paper, of means to convey sheets of paper from the table, a stamping block above the table, a plunger secured to the stamping block, a cylinder into which said plunger extends, a pressure cylinder, a pipe connecting the pressure cylinder and plunger, the driving shaft, a valve in said pipe and means actuated by the driving shaft to 120 actuate said valve while the paper conveying means are inoperative, an inking roller be-

neath the stamping block, and means pivotally supporting the inking roller from said cylinder and permitting the inking roller to move laterally when the plunger is depressed, and a spring tending to move the inking-roller under the stamping block.

5 In testimony of which invention, I have

hereunto set my hand, at Paulsboro, on this 21st day of October, 1907.

JOHN CHESNEY.
